UNITED STATES PATENT OFFICE.

OTTO L. OSTENDORF, OF ROCHESTER, NEW YORK.

CHAIR.

1,045,599.

Specification of Letters Patent. Patented Nov. 26, 1912.

Application filed April 24, 1912. Serial No. 692,880.

To all whom it may concern:

Be it known that I, Otto L. OSTENDORF, of Rochester, in the county of Monroe and State of New York, have invented certain new and useful Improvements in Chairs; and I do hereby declare the following to be a full, clear, and exact description of the same, reference being had to the accompanying drawings, forming a part of this specification, and to the reference-numerals marked thereon.

My invention relates to improvements in chairs, with particular reference to reclining chairs of the type embodying a swingingly movable back, and it has for its primary object to provide an improved construction and arrangement of parts for effecting vertical movement of the rear portion of the seat relatively to the back, when the back is lowered, and vice versa.

A further object of my invention consists in the provision of novel means for supporting the seat on the chair frame, and in connecting the seat with the back in such a manner as to obtain the necessary relative movement between them, so as to accommodate all positions of the body of a person in the chair.

To these and other ends the invention consists in certain improvements and combinations of parts all as will be hereinafter more fully described, the novel features being pointed out in the claims at the end of the specification.

Figure 1 is a vertical sectional view of a chair constructed in accordance with a preferred embodiment of my invention. Fig. 2 is a view in elevation, with the seat and back cushions removed. Fig. 3 is a vertical sectional view taken in the same plane as Fig. 1, the back being in lowered position, and the seat in correspondingly raised position. Fig. 4 is a detail sectional view, showing the connection between the back frame and the seat frame. Fig. 5 is a detail view in elevation, of the rack by which the back frame may be adjusted vertically, and Fig. 6 is a view in perspective of the hinge for connecting the seat frame to the base frame.

Similar reference characters throughout the several figures indicate the same parts.

In the present embodiment of the invention, 1 designates the base frame, 2 is the seat frame and 3 is the back frame, while 4 and 5 designate the cushions or upholstery

sections, which are suitably attached to the seat frame and back frame respectively.

The back frame 3 carries a transverse bar 6 which is adapted to be supported in any of the notches 7 formed in racks 8, whereby the back frame may be adjusted vertically to any one of three different positions, to accomplish a purpose which will be more fully set forth hereinafter. The back frame also carries suitable projections, preferably in the form of anti-friction devices 9, which coöperate with and support the seat frame in a manner which I will now explain.

The seat frame is pivotally supported at the front of the base frame, and includes side pieces 10 which are provided at their rear ends with reversely curved portions to which are attached correspondingly curved metal wear plates 11. The curved portions of the side pieces rest on the anti-friction devices 9, and the uppermost portions of the curved surfaces constitute seats for the anti-friction devices 9 when the chair parts are in their normal position as shown in Fig. 1, while the forwardly extending portions of the curved surfaces are so shaped that in their coöperation with the projections on the back frame, as the latter is lowered, the proper rise is given to the seat frame. That is to say, when the back is lowered, the rear portion of the seat frame is elevated a distance necessary to accommodate comfortably the body of the person in the chair, this being due to the formation of the cam surfaces with which the anti-friction devices 9 engage, as shown in Fig. 3. The parts are held in normal position by means of a tension spring 12 connecting the seat frame and the base frame, respectively, but it will be understood that the resistance offered by the spring is such that it may readily be overcome by pressure against the chair back.

The tension of spring 12 may be increased by raising the back frame from the position shown in the drawings, and supporting it in one of the upper pairs of notches 7. This effects a raising also of the seat frame, thus creating a greater tension on the spring 12. This adjustment is desirable for persons of different weight so that the resistance offered will be proper under all conditions, to insure comfort, and it will be understood that while I have shown three possible adjustments for the back frame, I may employ a structure enabling a greater or smaller

number of adjustments without departing from the essential idea of my improvement.

The seat frame 2 is pivotally and removably attached at the front of the base frame, and to this end I attach to the base frame, 5 the hinge leaves 13 which are preferably provided with rearwardly upturned portions 14 and are slotted at 15. The seat frame carries coöperating hinge leaves 16, 10 which have angular lugs 17 adapted to engage in the slotted portions 15 of the leaves 13. This forms a simple and extremely efficient hinge, permitting ready movement of the seat frame about its pivotal axis, and 15 enables the seat frame to be removed from the base frame by lowering it at the rear, after the back frame is removed. It will be understood that the weight of the parts, together with the spring 12, holds the back frame in its normal position, in which it 20 supports the seat frame, and prevents removal of the latter. To take the chair apart, the spring 12 is first removed, and the back can then be lifted out, leaving the seat 25 free to be detached from its hinge supports.

I claim as my invention:

1. In a chair, the combination with a base frame, of a seat frame pivotally supported at the front of the base frame, the seat frame 30 including side pieces each having a reversely curved portion formed thereon, a back frame pivotally supported on the base frame, and projections on the back frame having engagement with the reversely curved portions 35 of the side pieces.

2. In a chair, the combination with a base frame, of a seat frame pivotally supported at the front of the base frame, the seat frame including side pieces each having a 40 reversely curved portion formed thereon, a

back frame pivotally supported on the base frame, and anti-friction devices carried by the back-frame and engaging said curved portions of the side pieces.

3. In a chair, the combination with a base frame, of a seat frame pivotally supported at the front of the base frame, the seat frame including side pieces each having a curved portion formed thereon, metal wear plates secured to said curved portions and 45 conforming to the curvature thereof, a back frame pivotally supported on the base frame, and anti-friction devices carried by the back-frame and engaging said metal plates on the side pieces. 50

4. The combination with a base frame, of a seat frame pivotally supported at the front of the base frame, the seat frame including side pieces each having a reversely curved portion formed thereon, metal wear 60 plates secured to said curved portions, a back-frame adjustably supported on the base frame, anti-friction devices carried by the back frame and engaging said curved portions of the side pieces, and a spring connecting the base frame and the rear part of 65 the seat frame.

5. In a chair, the combination with a base frame, of a seat frame pivotally supported at the front of the base frame, the seat frame 70 including side pieces each having a cam surface at the rear thereof of extended, gradual curvature, a back-frame pivotally supported on the base frame, and projections on the back frame having engagement with said 75 cam surfaces.

OTTO L. OSTENDORF.
